United States Patent Office

Des. 212,826
Patented Nov. 26, 1968

212,826

COMBINED PITCHER AND COVER THEREFOR

Robert A. Claridge, Charlotte, N.C., assignor to South-
eastern Plastics Corporation, Charlotte, N.C., a corpo-
ration of North Carolina

Filed Feb. 7, 1968, Ser. No. 10,485

Term of patent 14 years

(Cl. D44—21)

FIG-6FIG-7FIG-8FIG-9FIG-10

FIG. 1 is an isometric view of a combined pitcher and cover therefor showing my new design;

FIG. 2 is a reduced scale front elevational view;

FIG. 3 is a side elevational view on the same scale;

FIG. 4 is a rear elevational view on the same scale;

FIG. 5 is a top plan view on the same scale;

FIG. 6 is an isometric view on the same scale as FIG. 1, of a combined pitcher and cover therefor showing another embodiment of my new design wherein the cover member is cut back at the lip;

FIG. 7 is a reduced scale front elevational view;

FIG. 8 is a side elevational view on the same scale;

FIG. 9 is a rear elevational view on the same scale; and

FIG. 10 is a top plan view on the same scale.

I claim:

The ornamental design for a combined pitcher and cover therefor, substantially as shown and described.
